UNITED STATES PATENT OFFICE.

OTTO WUNDRACK, OF MAYWOOD, ILLINOIS.

MECHANICAL STOKER.

1,162,965.

Specification of Letters Patent.

Patented Dec. 7, 1915.

Application filed October 12, 1914. Serial No. 866,264.

To all whom it may concern:

Be it known that I, Otto WUNDRACK, a citizen of the United States, and a resident of Maywood, in the county of Cook and State of Illinois, have invented certain new and useful Improvements in Mechanical Stokers; and I do hereby declare that the following is a full, clear, and exact description thereof, reference being had to the accompanying drawings, and to the letters of reference marked thereon, which form a part of this specification.

This invention relates to improvements in mechanical stokers for furnaces and consists of the matters hereinafter described and more particularly pointed out in the appended claims.

The object of the invention is to provide a simple and efficient mechanism for feeding the fuel evenly over the grate surface, together with means whereby the amount of fuel admitted or fed to the grate may be regulated as required without stopping the operation of the stoker.

Other objects and advantages will appear as I proceed with my specification.

In the drawings: Figure 1 is a view in front elevation of a stoker made in accordance with my invention, illustrating the same in a position for feeding fuel to the interior of a furnace. Fig. 2 is a longitudinal vertical sectional view through a furnace to which my improved stoker has been applied, the plane of the section being indicated by line 2-2 of Fig. 1. Fig. 3 is a detail sectional view on an enlarged scale, the plane of the section being indicated by line 3-3 of Fig. 1. Fig. 4 is a detail sectional view, the plane of the section being indicated by line 4-4 of Fig. 3. Fig. 5 is a detail sectional view on an enlarged scale the plane of the section being indicated by line 5-5 of Fig. 2. Fig. 6 is a detail longitudinal vertical sectional view on an enlarged scale through the grate bars at the lower inner end of the stoker. Figs. 7, 8 and 9 respectively are face views in elevation of several of the fuel feed controlling disks which will be more specifically referred to as I proceed with my specification.

Referring now to that embodiment of my invention as illustrated in the accompanying drawings:—The furnace (see Fig. 2) in connection with which my improvements are shown herein, is of the open front type,

which open front is closed by the front wall of the stoker when said stoker is in operative position in the furnace. Said furnace is provided with an arch wall 10 and with an overhanging bridge wall 11 the space between the arch wall and the top of the bridge wall constituting a conduit by which the hot gases from the combustion chamber 12 are directed into contact with the usual boiler of the plant of which the furnace forms a part. The furnace has an ash pit 13 the bottom of which is preferably located below the floor level of the engine room where the furnace is located and which extends outwardly beyond the open front of the furnace a suitable distance.

Referring now to the stoker proper 15—15 indicate side frame members which are so arranged that their inner faces are flush with the inner faces of the side walls of the furnace when the stoker is in operative position in the furnace. Said side frame members are rigidly connected together at their rear ends by a transversely extending channel bar 16. The front ends of said members 80 rise higher than their rear ends and are rigidly attached to a front wall plate 17 which is adapted to close the open front of the furnace, with its lateral marginal parts engaging against and overlapping the front ends of the furnace side walls.

The side frame members 15, the channel 16 and the front plate 17 together constitute a carriage upon which the various operative parts of the stoker are supported. The 90 rear end of said carriage is provided with flanged wheels 19—19 which are mounted upon stub shafts 20 that are fixed to and extend inwardly from the side frame members 15. The front end of said carriage is likewise provided with flanged wheels 21 mounted upon similarly supported stub shafts 22 near the forward ends of the frame members 15. The wheels 19 and 21 roll upon rails 23 fixed to the bottom of and extending the full 100 length of the ash pit 13.

The inside faces of the front wheels 21 have fixed to and concentric with them beveled gears 24 which mesh with beveled pinions 25 fixed to the inner ends of horizontally extending shafts 26 that have rotative bearing in the front wall 17 of the stoker carriage. The opposite ends of said shafts project outwardly from the front face of the plate 17 and are each squared to receive a 110

5 the interior of the furnace.

At the sides of the stoker frame are located bars 27-27, having hooks 28 by means of which they are hinged to swing up and down on lugs 29 fixed to the rear face of the 10 stoker front wall 17 at about the level of the top of the bridge wall 11. Said bars 27 constitute supports for the grate bars and are inclined downwardly and rearwardly toward the bridge wall and terminate in horizontal 15 extensions 30 which project into the vicinity of the over hanging ledge of the bridge wall 11. The ends of said horizontal extensions rest upon a transversely extending, flat bar or support 31, which in turn rests at its 20 ends upon upright adjusting screws 32. The said screws are threaded through horizontal flanges 33 on the side frame members 15. Lock nuts 34 are provided on said screws 32 to hold them against rotation after they 25 have been adjusted to bring the supporting bar 31 to the desired position. The rear ends of the side frame members 15 are arranged to provide vertical guiding surfaces 35-35 which prevent displacement of the 30 transverse support 31.

It is apparent from the above description that the rear ends 30-30 of the bars 27 may be independently raised and lowered about the lugs 29. Such flexibility is of advantage 35 for purposes of adjustment where there are any inequalities due to the construction of the furnace and also to give the required inclination to the grate supported by said bars for proper feeding of the fuel over said 40 grate.

The bars 27 are provided with upwardly opening notches 36 adapted to receive and form bearings for trunnions 38 formed at the ends of transversely extending rocking 45 grate bars 37. Each grate bar 37 has a plurality of parallel, spaced, rearwardly extending short bars 39 which extend into the vicinity of the next adjacent grate bar to the rear and which, together with the bar 37, 50 constitute a sectional grating, the whole number of the sectional gratings thus formed comprising the grate of the stoker. Each grate bar 37 is also provided at its ends with downwardly extending rock-arms 40-40 55 and the rock-arms of all the sectional gratings are pivotally connected to inclined links 41, 41, one of said links being at one side of the stoker, and the other at the opposite side thereof. A connecting rod 42 is attached 60 to each link 41, the outer end of said connecting rod projecting through suitable openings in the front plate 17 and being there provided with an eccentric strap 43. Each strap 43 embraces an associated eccentric disk 44 that is rigidly attached to and

rotates with a horizontal shaft 45, extending transversely in front of the stoker, and mounted in suitable bearing blocks 46 fixed to the front wall plate 17 thereof. The shaft 45 projects at one end beyond the lateral edge of the front wall plate 17 and has fixed to it at that end, a ratchet wheel 47. Adjacent said ratchet wheel 47 and having bearing thereon, is located a rocking bell crank lever 48 with a vertical arm carrying a pawl 49 adapted for engagement with the teeth of the ratchet wheel 47 and a horizontal arm provided with a slot 50 in which is mounted a bearing block 52 that is pivotally connected to a vertically reciprocating rod 51. The bearing block 52 is capable of adjustment within the slot 50 of the bell crank lever so that the "throw" of said lever may be regulated, thus controlling the rotative speed of the shaft 45. It is apparent that vertical reciprocation of the rod 51 will cause a rocking movement of the bell crank lever 48 and the said rocking movement will impart to the shaft 45 a rotative step by step movement through the action of the 90 pawl 49 and the ratchet wheel 47. The rotation of the shaft 45 will, through the eccentrics 44-44, produce a reciprocating movement of the rods 42 and links 41 to which the rock arms 39 of the grate bars 37 95 are pivotally connected, and a resulting rocking movement of the sectional gratings comprised by the grate bars 38 and the bars 39. The rocking of the sectional gratings will cause the fuel on the inclined grate of the 100 stoker to be advanced downwardly and rearwardly and manifestly this advance of the fuel may be so adjusted that, when the fuel reaches the rear end of the grate it will be thoroughly burned, leaving only a residue 105 of ash.

It is desirable to remove the ash left at the rear of the grate from the combustion chamber at certain times and also to break up any clinkers or the like left at the rear 113 of the grate without interfering with the continuous feed of fuel over the grate. Such means are provided as follows:

55 indicates a hand controlled clinker breaking bar which when in one position 115 forms a part of the grate surface. Said bar (see Figs. 1, 5 and 6) comprises a plurality of spaced, sector plates 56 placed in between the short bars 39 of the lowermost sectional grating. Said sector plates are made integral with a rock bar 57 the ends of which are provided with trunnions 59 having suitable bearing in notches 36a formed in the upper edges of the grate supporting bars 27 near the lower end thereof. 60-60 indicate 120 downwardly extending rock arms rigidly attached to the rock bars 57. The said rock arms are pivotally connected to inclined operating rods 61 which project through apertures 62 formed in the front wall 17 of 130

the stoker. Notches 63 are formed in the lower edge of each of the rods 61 for engagement with the bottom wall of the associated aperture 63 through which it extends, to hold said clinker bar in fixed position. The forward end of each bar 62 is provided with a hand loop 64 for convenience in operating said rod.

65 indicates an ash and clinker holding 10 and supporting grate. Said ash grate is arranged to receive the burnt fuel after the same has traveled over and has been discharged from the grate bars 37. Said ash grate comprises a horizontal rectangular 15 frame 66 the end members of which are connected by integral grate bars 67. The front end transverse member of said grate extends into the vicinity of and adjacent the bar 57 of the clinker member. The rear end trans- 20 verse member extends into the vicinity of the vertical plane of the overhanging ledge of the bridge wall 11 and said frame member is provided with trunnions 68 which have bearing in upwardly opening notches 25 69 formed in the upper edge of the horizontal extensions 30 of the grate supporting bars 27. To the forward end member of the grate 65 are attached downwardly and forwardly extending arms 70 which are piv- 30 otally attached to operating and supporting bars 71. Said bars extend upwardly and forwardly and project through suitable ap- 35 ertures in the front plate 17. Said bars are likewise provided with notches in their lower edges which coat with the bottom walls of the aperture in the front wall through which they pass in the same way as in the case of the bars 61. The forward ends of the bars 71 are likewise provided with hand loops 72.

40 When it is desired to relieve the rearmost sectional grating of the stoker grate of its accumulated cinders and ashes and to break up the clinker formation thereon, the bar 61 is raised to disengage it and is then reciprocated forwardly and backwardly to 45 rock the clinker grate bar 55 from the position shown in Fig. 2 to that shown in Fig. 6. This rocking movement of said grate bar will break and raise such clinkers as will 50 have formed at this point and deposit the greater amount of them upon the ash grate 65. When it is desired to dump the ash grate the clinker bar 55 is left in the position shown in Fig. 6. When in this position said bar forms an abutment or stop for holding back the fuel upon the inclined grate of the stoker. The hand lever 71 supporting and holding the forward end of the ash grate, is moved upwardly to disengage 55 it and is then moved rearwardly, thus permitting the forward end of said grate to drop or swing about upon its trunnions 68. This movement will incline the forward end of said grate downwardly and the ashes, 60 clinkers and the like thereon, will then fall

into the ash pit 13. The ash grate 65 is then returned to its normal position as shown in Fig. 2.

To remove the ashes from the ash pit the front wall plate 17 is provided with a door 70 75 which is adapted to swing downwardly about its bottom edge to open for the admission of the usual pull iron or hoe for the removal of the ashes from the ash pit. When the ashes have been removed from the 75 ash pit the door 75 is then closed.

The front plate 17 of the stoker is also provided just above the door 75 with doors 76. Said doors 76 are of a greater height than the door 75 and swing about vertical 80 axes to be opened and closed and permit of an inspection of the under surface of the grate bars 38. Said doors may be also used to control the draft of air admitted to the 85 interior of the furnace.

The means for feeding fuel to the grate of the stoker are as follows: To the upper end of the front wall plate 17 is attached and supported a fuel hopper 80. Said hopper 80 comprises an upwardly and outwardly inclined front wall 81, upright side walls 82-82 and an upright rear wall 83. The rear wall 83 is spaced a suitable distance inwardly from the front wall plate 17 and when the stoker is in operative position relative to the furnace to which it is applied, said wall will abut against the front of the throat arch 10^a of the arch wall with its lower edge at a level approximating the level 90 of the throat arch 10^a. The lower inner end 95 of the front wall 81 is made in arcuate form as at 84. 85 indicates a transversely extending plate which is attached at its upper edge to the rear plate 83 of the hopper. Said plate is provided with a downwardly and 100 forwardly inclined portion 86 which terminates short of the plate 81 to form a discharge opening 80^a and an arcuate portion 87, said arcuate portions 84 and 87 respectively forming an auxiliary hopper 88, which 105 communicates with the main hopper 80 by means of said discharge opening 80^a. The inner end of the arcuate portion 84 of the plate 81 terminates short of the lower edge 110 of the plate 85 to form a discharge passage 115 or opening 89 connecting said auxiliary hopper 88 with the interior of the furnace.

Concentrically arranged with respect to the arcuate walls 84 and 87 of the said auxiliary hopper is located a square shaft 90 the 120 ends of which are cylindrical and which have suitable bearing in the end plates 82 of the main hopper in a manner permitting rotation of said shaft. Mounted on said shaft 90 intermediate the side walls 82 of the hopper so as to rotate therewith is located a star feed device 91 having four concave side walls 91^a which form pockets each capable of holding a certain amount of fuel as it falls from the main hopper 80 through the discharge 130

opening 80^a at the bottom thereof. It is apparent that with the rotation of the shaft 90 the feed device 91 will discharge the fuel at a certain regular rate through the discharge opening 89 at the bottom of said auxiliary hopper 88 upon the grate of the stoker. The feed device 91 is adapted for rotative movement in a step by step manner and the means for imparting such step by step rotative movement is as follows: One cylindrical end of the shaft 90, preferably the left hand end as viewed in Fig. 1, extends outwardly a suitable distance through and beyond a bearing 92 fixed to the front wall plate 17. Keyed to said shaft intermediate its end and the bearing 92 is a ratchet wheel 93. Adjacent the outer face of said ratchet wheel and loosely mounted on said shaft is a bell crank lever 94 having a hub 94^a. The said bell crank lever comprises a vertical arm 95 and a horizontally extending arm 100. The vertical arm 95 of said bell crank lever carries a pivoted pawl 96 which is located in the vertical plane of and adapted 25 to intermittently engage and actuate the ratchet wheel 93. Said vertical arm also carries on its other side a second pawl 97 which engages with and actuates a second ratchet wheel 98 of smaller diameter, loosely 30 mounted upon the hub 94^a of the bell crank lever 94. A collar 99 fixed to the end of the shaft 91 retains said pawls and bell crank lever from endwise displacement upon said shaft.

35 The horizontal arm 100 of said bell crank lever projects forwardly beyond the plane of the front wall plate 17 and is provided with a slot 101 near its forward end. In said slot is adjustably mounted a bearing 40 block 102 to which is pivotally connected the upper end of a vertically reciprocating rod 103. The reciprocating movement of said rod produces a rocking movement of said bell crank lever 94 about the shaft 91 as an 45 axis.

50 Fixed to the outer face of the ratchet wheel 98 by means of suitable bolts 98^a is a plurality of superposed feed controlling disks 105, 106, 107 and 108. (See Figs. 3, 7, 8 and 9 respectively), each of which has a different peripheral contour. As shown in Fig. 3, the disk 105 is provided upon its periphery with equally spaced teeth or lugs 105^a with like shaped depressions 105^b between them.

55 110 indicates a horizontally extending square bar which is adjustably mounted in a square opening formed in the pawl 96. Said bar may be adjusted inwardly and outwardly through said pawl 96 and locked in the desired position therein by means of a fly nut 111. The outer end of said bar 110 is provided with an angularly arranged finger 110^a which is adapted to engage the periphery of any of the desired feeding disks 60 105, 106, 107 and 108, depending upon the adjustment of the bar 110. The finger 110^a is so proportioned with respect to the pawl 96, that when its free end is in engagement with one of the depressions 105^b of the disk 105 the pawl 96 will rotate about its pivot 70 and engage one of the teeth of the ratchet wheel 93. During the rotation of the ratchet wheel 98 and with it the several feed controlling disks before mentioned, the finger 110^a will ride upon one of the teeth 105^a of the disk 105 causing the free end of said finger to engage and carry with it the pawl 96 so as to disengage the same from the teeth of the ratchet wheel 93. 75

80 The operation of the feed mechanism is as follows: As before explained the vertical reciprocation of the rod 103 will cause the bell crank lever 94 to rock or oscillate about its axis. This rocking movement will cause the pawl 97 to engage with one of the teeth of the ratchet wheel when the vertical arm of said lever is moving forward, and rotate said wheel a distance equal the distance between adjacent teeth. When the arm moves rearwardly the pawl 97 will drag over the inclined face of the succeeding tooth and will engage the radial face of said tooth so that when the vertical arm again moves forward the wheel will again be advanced the 90 distance of one tooth. The ratchet wheel in this manner is given a step by step rotative movement and the disks 105, 106, 107 and 108 will be advanced a like radial distance. 95 When the finger 110^a is engaged within any 100 of the recesses 105^b of the disk 105 the pawl 96 on the vertical arm 95 will be in engagement with the tooth of the ratchet wheel 93 and on the forward movement of said arm said pawl will advance the ratchet wheel a 105 distance of one tooth. Said ratchet wheel being keyed to the shaft 91 will rotate the same a radial distance equal one tooth. On the rearward rocking movement of the vertical arm 95 of the bell crank lever 94 the 110 pawl 97 will drag over the now stationary ratchet wheel 98 and the finger 110^a will also drag or ride over the tooth 105^a. This dragging movement will cause the pawl 96 to be lifted upwardly about its axis so that when 115 the finger 110^a is engaging the top of the tooth 105^a said pawl will be free from engagement with the ratchet wheel 93. Should the bar 110 be adjusted through the pawl 96 so that the finger would be in engagement 120 with the top surface of one of the broad teeth 106^a of the disk 106 said pawl will be held out of engagement with the teeth of the ratchet wheel 93 as long as the finger 110^a is in contact with the top of said teeth. 125 When the finger 110^a is in engagement with the depression 106^b of said disk said pawl 96 would be in engagement with one of the teeth of the ratchet wheel 93 and upon a forward movement of said arm the said wheel 130

and shaft 91 would then be rotated forwardly one step. I have illustrated the disks 107—108 as having different shaped or length of teeth 107^a, 108^a, separating said teeth. It is apparent that the teeth and depressions may be arranged so that any kind of desired feed of fuel may be delivered to the stoker, such feed of course depending upon the contour of the feed disks. As the fuel is fed from the auxiliary hopper 88 through its discharge opening 89 said fuel falls upon an inclined transversely extending plate 120. Said plate is pivotally supported at its forward edge on a rod 121 which is fixed at its ends in the side walls 82 of the main hopper 80 at a point below the arcuate wall 84 of the auxiliary hopper 88. The said plate extends rearwardly and downwardly from its pivotal axis and the free edge thereof is arranged to overlap the forward end of the stoker grate. Fixed to said plate 120 adjacent the rod 121 are laterally arranged forwardly extending bars 112 which extend through suitable slots formed in the front wall plate 17. Said bars are provided with adjustably mounted weights 113 so arranged upon said bars as to approximately counterbalance the weight of the plate 120. 114 indicates a downwardly and rearwardly inclined plate, which is pivotally mounted adjacent its front edge upon ears 115 fixed to the front plate 17. The rear free edge of said plate projects into the vicinity of and is arranged to support the free edge of the plate 120. Should it be desired to view the interior of the furnace or to momentarily shut off the feed of fuel from the hopper 80 without stopping the operation of the stoker, said plate 120 may be swung upwardly to the position indicated in dotted lines in Fig. 2 so as to close off the feed of fuel from the auxiliary hopper by exerting a downward pressure upon the rods 112. When said plate 110 is in the position noted, a door 115 provided in the front plate 17 may be opened, when full view may be had of the interior of the furnace.

While in describing my invention I have

referred to certain details of mechanical construction and arrangement of parts, I do not wish to be limited thereto except as may be pointed out in the appended claims.

I claim as my invention:

1. In combination with a stoker, means for feeding fuel to said stoker, comprising a hopper, a rotative shaft, a fuel feeding device for delivering fuel from the hopper to the stoker fixed on said shaft, a ratchet wheel 60 fixed to said shaft, a second ratchet wheel loosely mounted on said shaft, a rock arm, pawls carried by said arm adapted for engagement with said ratchet wheels, and means operated by one of said ratchet wheels 65 for controlling the effective movement of the other ratchet wheel.

2. In combination with a stoker, means for feeding fuel to said stoker comprising a hopper, a rotative shaft, a fuel feeding device for delivering fuel from the hopper to the stoker fixed on said shaft, a ratchet wheel 70 fixed to said shaft, a second ratchet wheel loosely mounted on said shaft, a rock arm, pawls carried by said arm adapted for engagement with said ratchet wheels, and means carried by the said loosely mounted ratchet wheel for controlling the operative engagement of one of said pawls with respect to the said fixed ratchet wheel.

3. In combination with a stoker, means for feeding fuel to said stoker comprising a hopper, a rotative shaft, a fuel feeding device for delivering fuel from the hopper to the stoker fixed on said shaft, a ratchet 85 wheel fixed to said shaft, a second ratchet wheel loosely mounted on said shaft, a rock arm, pawls carried by said arm adapted for engagement with said ratchet wheels, and means whereby said controlling means may 90 be varied.

In testimony, that I claim the foregoing as my invention I affix my signature in the presence of two witnesses, this 20th day of September, A. D. 1914.

OTTO WUNDRACK.
